INDUCTION SYSTEM FOR INTERNAL-
COMBUSTION ENGINES

Maryan Cieclerski, Jr., Jersey City, N. J.

Application April 7, 1943, Serial No. 482,132

2 Claims. (Cl. 123—122)

This invention relates to induction systems for internal combustion engines of the type which normally utilize a carburetor for admixing air and fuel exteriorly of the engine and feed the so-called carbureted mixture to the intake manifold of the engine, through which it is distributed to the several cylinders.

By the present invention the carburetor is entirely eliminated and the mixture of the fuel with the air, to form a motive mixture, is effected within the cylinders of the engine.

According to the present invention, air is admitted to the cylinders through the usual manifold or directly into the individual cylinders without the necessity of employing a manifold and the fuel is also introduced directly into the cylinders to form the combustible mixture therein.

An important feature of the present invention is that the fuel is maintained in liquid form until it enters the cylinders of the engine and it is peculiar to this invention that the fuel is fed to the cylinders in highly heated liquid form and under considerable pressure. It is delivered in this condition to the cylinders but, as it is discharged into the cylinders, this discharge is accompanied by such rapid expansion of the fuel that it is immediately vaporized or gasified.

In a four cycle engine operating according to the present invention, air is drawn into the cylinders for the full suction strokes thereof, but the fuel is admitted to such cylinders preferably near the end of the suction stroke and just before the commencement of the compression stroke. This procedure allows the maximum amount of air to enter the cylinders and the fuel injection will not be opposed by pressure which would be present in the cylinders if the fuel were admitted during the compression stroke.

In order to condition fuel for injection into the engine cylinders as specified, it is first heated to a temperature higher than its boiling point at atmospheric pressure. This heating takes place within a fuel conditioner having a fuel confining chamber which will be hereinafter termed the pressure chamber. This chamber may be electrically heated or otherwise, but may be conveniently heated by jacketing it and passing through the jacket the waste products of combustion of the engine, so that fuel pumped into the pressure chamber from a suitable source of fuel supply may be heated therein to the desired temperature with coincident building up of a relatively high vapor pressure head in the pressure chamber.

From the pressure chamber the liquid fuel is

fed through an appropriate speed control valve to a distributing chamber, connected by relatively small tubes to injector nozzles associated with the respective cylinders. These injector nozzles are positively controlled by any appropriate means synchronized with the timing of the engine, so as to open in proper timed relation with the movements of the pistons in said cylinders, whereby the fuel may be fed in liquid condition under high pressure and temperature to the nozzles and admitted to the respective cylinders near the end of the suction stroke in each of them. In this way the fuel is maintained in liquid condition until it passes through the nozzles into the cylinders and these nozzles perform the function of expansion valves, so that, as the fuel passes through the nozzles into the cylinders, it is transformed from liquid into vapor or gaseous state where it readily admixes with the air already in the cylinders, assists in the heating thereof, and brings about a highly combustible motive mixture. In practice, the duration of opening of the several injector nozzles is adjusted to meet the requirements of the engine by insuring a proper mixture of air and fuel.

The speed of the engine is controlled by the speed control valve to which reference has been made for, through manipulation of this valve, the pressure in the fuel distributing chamber and at the pressure nozzles may be controlled.

As hereinbefore stated, the fuel is preferably heated within the pressure chamber by passing waste products of combustion from the engine through the jacket of said chamber. The apparatus for carrying out this operation will be presently described, but it may be here noted that the passage of such hot waste products of combustion through said jacket is preferably controlled, according to this invention, by a heat governor which, when the fuel in the pressure chamber is at the desired heat and pressure, will serve to automatically bypass the waste products of combustion from the jacket directly to the atmosphere and thus preclude overheating of the fuel.

Fuel is supplied to the pressure chamber from a suitable source through a pump and between the pump and said chamber is a pressure controller which is automatically operable, after the manner of a safety valve, to preclude the building up of excessive pressures in the pressure chamber by leading excess pressure back to the fuel supply line or storage tank.

The primary elements which enter into the system of this invention individually embody various

novel features which will presently be described in detail. Of importance in this connection, is the structure of the pressure chamber. In the system of this invention, it is desirable that this chamber carry a sufficient amount of fuel, under relatively high temperature and pressure in order to fulfill the requirements of the engine. At the same time it is equally desirable to maintain a vapor space above the surface of the fuel, so that, as the pressure on the fuel increases, due to heating thereof, the vapor within this space may be compressed, in accordance with well known steam-dome principles to exert an elastic pressure upon the surface of the fuel and thus materially facilitate the feeding of such fuel at high pressure and temperature to the injector nozzles.

In order to insure the presence of this vapor cushion at all times, the present invention provides a float control for the feed of liquid fuel into the pressure chamber from the feed pump and the float control means employed for this purpose is such as to compensate automatically for variations in position of the system as a whole. For example, if the system is incorporated in an aircraft, it will not be at all times in any particular position for, while the aircraft is in flight the latter may dive, climb, roll or bank and these movements will of course affect the level of the liquid in the pressure chamber. Consequently a float to be controlled by such liquid level must be so arranged as to compensate for the movements of the aircraft and the present invention so provides, as will be apparent from the detailed description of the drawing which follows.

In the drawing I have illustrated the preferred embodiment of the induction system of the present invention but the showing therein made is to be understood as for illustrative purposes only and not as defining the limits of the invention.

The drawing illustrates only such detail as is required for a clear understanding of the invention and where conventional parts are shown, they are illustrated in a more or less diagrammatic manner, the showing nevertheless being such that one skilled in the art may readily construct and use the same through application of the principles herein described.

In said drawing,

Figure 1 illustrates this invention in a more or less diagrammatic way, certain parts being shown in section in the interest of clearness.

Figure 2 is a section on the plane of the line 2-2 of Figure 1.

Figure 3 is a section on the plane of the line 3-3 of Figures 1 and 2.

Figure 4 is a vertical section showing more or less diagrammatically the construction and operation of one of the injector nozzles.

Figure 5 is a fragmental section of a modified form of float valve fitting.

Referring to the drawing, 1 is a pipe leading from a fuel supply tank to a pump 2 from which a pipe 3 leads to the pressure chamber 4 with the surrounding jacket 5. The pressure chamber and jacket are preferably spherical in form although they may be cylindrical if desired. At the point where the pipe 3 connects with the pressure chamber 4, it communicates with a duct 6, which extends radially of said chamber and within the confines of the chamber this duct is of globular form so as to provide a spherical socket 7.

Within the pressure chamber is a float valve assembly which, for illustrative purposes, is shown in the drawing as of one-piece casting or fitting

11, although, in practice, it may be otherwise built or fabricated as desired. In any event it is provided with a tubular radial trunnion 9 provided with a ball-like enlargement 8 rotatably fitted within the socket 7. A straight through passage 10 extends through said trunnion radially of the pressure chamber. The fitting 11 is positioned substantially centrally of the spherical or cylindrical pressure chamber. It is provided therein with a valve chamber 12 having a valve seat 13 for cooperation with a valve 14. The stem 15 of the valve extends upwardly through a guide 16 and is secured at its upper end to a float 17. The valve stem 15 is so associated with the guide 16 as to permit the stem to vertically reciprocate in the guide but preclude relative rotation between them. This may be accomplished in any desired way, as by a key, but, in Figure 3, where a cross section of the valve stem and guide are shown, the stem 15 is illustrated as of non-circular curvilinear cross section while its guide 16 is of a like shape so that the stem cannot rotate within the guide.

The upper end of the valve stem 15 is pivotally secured to the float 17, by means of a pin 18, as shown in Figures 1 and 2, the sealed float being provided with a re-entrant portion 19 into which the upper end of the valve stem may extend for cooperative relation with the pin 18 of the float.

The axis of the passage through the trunnion 9 is preferably arranged fore and aft of an aircraft when the system of this invention is installed therein, while the pin 18 extends in a port and starboard direction, so that by virtue of the pin connection shown, the float is adapted to tilt to compensate for changes in liquid level as the aircraft climbs or dives.

Above the valve chamber 12 and communicating with the seat 13 in the fitting 11 is a passage 20 which leads downwardly to near the bottom of the pressure chamber (see Fig. 1), so that fuel fed from the pump 2 through the pipe 3 to the valve chamber 12 may, when the valve is opened, pass through the duct 20 into the lower part of the pressure chamber to raise the liquid level therein until it reaches such elevation that the float 17 will lift the valve 14 and shut off the supply of fuel. When the valve 14 is thus closed, the pump 2 need not stop. It may continue to operate for I have provided the pressure controller 21. This controller is connected with the pipe 3 through a branch 22 which communicates with a cylinder 23 and in this cylinder is a piston 24 normally depressed by a spring 25, the tension of which may be controlled by an adjusting screw 26.

The adjustment should be such that so long as the pressure in the pressure chamber is below that desired, the spring will depress the piston 24 below a feed-back pipe 27 and thus fuel passed through the pump will be delivered to the valve chamber 12. However, when this valve is closed, or when the pressure in the pressure chamber exceeds that predetermined, then back pressure will be exerted through the branch 22 to raise the piston 24 and relieve the pressure through pipe 27 which feeds back to the fuel tank.

The fitting 11 also carries a fuel outlet duct 28 which is open in the upper portion of the pressure chamber and has a trunnion 29 which rotatably fits into a radial socket 30 positioned diametrically opposite the socket 7. The trunnions 29 and 9 are thus in radial axial alignment with one another (and coaxially with the pressure chamber if the latter is cylindrical) and they are all mounted for free rotation within the

closely embracing portions of their respective sockets in the pressure chamber. Consequently, when the pressure chamber is rotated about the common axis of these parts, the float will maintain the float valve assembly in upright position at all times for, as the liquid in the pressure chamber shifts within said chamber, the float will shift with it and in so doing will maintain the valve stem 15 in substantially upright position at all times. In this way, banking of the aircraft, or its various position in executing a roll, etc., are compensated for.

With the fitting constituted as described, fuel fed from the pump at substantially atmospheric temperature will be fed by pump 2 into the pressure chamber near the bottom thereof, while fuel from the upper portion of the pressure chamber, in heated condition and under considerable pressure, is adapted to be fed through the outlet duct 28 into and through trunnion 30 and to pipe 31 and through the speed control valve 32 to a distributing chamber 33. The speed control valve may be of any desired type and it may be either manually or automatically controlled, whereby the amount of fuel fed to the distributing chamber may be regulated. The distributor chamber 33 may be of any desired shape. It merely serves as a feed cavity for the connection of a number of relatively small fuel distributing tubes 34 which lead to the injector nozzles 35, one of which is associated with each cylinder. All these distributor tubes are preferably heat insulated or placed near to or in the hot exhaust lines to prevent an excessive drop in temperature of the liquid heated fuel passing through said tubes.

The structure of the injector nozzles may vary within wide limits, but a satisfactory form of construction is shown in Fig. 4. Here a valve housing 38 has a threaded shank adapted to be screwed into a cylinder head 37, so that the valve may discharge through a passage 38 into the engine cylinder. The valve has therein a seat 39 for cooperation with a sealing member 40, the stem 41 of which passes upwardly through a packed joint and has associated therewith a spring 42 which normally lifts the stem 41 to close the valve. The upper end of the stem is operated by a rocker arm 43 pivoted at 44 and acted upon by a push rod or tappet 45, in turn actuated by a cam 46, operable in timed relation to the engine. One of the fuel distributing tubes 34 is shown as connected to the valve casing above the seat 39 and the valve opens inwardly as illustrated, so as not to be inadvertently unseated during the compression or firing strokes of the piston. The fuel injector may be operated in other ways than by the rocker arm and tappet arrangement shown, as will be well understood by those skilled in the art.

The exhaust manifold 47 is connected by a pipe 48 to a duct 49 which has two branches 50 and 51. The branch 50 leads directly into the jacket 5 of the pressure chamber, while the branch 51 leads to the atmosphere. Interposed in the branch 50 is a slide valve 52, the stem 53 of which is connected to a piston 54 and this piston operates within a cylinder 55 of a heat governor. A spring 56 normally retracts the piston to withdraw the valve 52 from the branch 50, but the rear end of the piston is connected by a pipe 57 to the fuel outlet pipe 31 of the pressure chamber.

So long as the pressure in the pressure cylinder 4 is below that required, the spring 56 will withdraw the valve 52, so that the hot exhaust

gases from the engine will pass in a straight-through direction from the pipe 48 through the passage 50 into and through the jacket 5 of the pressure chamber, to be exhausted, after passing therethrough, to the atmosphere through an outlet 58. However, when the temperature and consequent pressure in the pressure chamber are elevated to the point desired, the pressure within this chamber will be communicated through the pipe 57 to the cylinder 55 to force the piston 54 to the right in Fig. 1 and close the valve 52, so that the hot exhaust gases will exhaust to the atmosphere through the branch 51 until further heating of the liquid in the pressure chamber is required. These operations are absolutely automatic.

In the system described practically every portion thereof is automatic in its operation except the operation of the speed control valve 32 and this, if desired, may be rendered automatic by a speed governor or any other suitable appliance known to the automotive arts.

To initiate operation of the system, it is of course necessary to first heat up the engine or at least the pressure chamber, to a point where it will deliver motive fuel at the pressure and temperature required to function as described. In practice, the engine may be started by an auxiliary carburetor associated with the intake manifold and operated in the conventional manner until the engine heats up and the exhaust gases thereof can raise the temperature of the fuel in the pressure chamber, as described. However, if preferred, electrical heating elements may be associated with the pressure chamber to initially furnish the heat desired for its proper operation.

It will be noted from Figure 1 that the uppermost portion of the pressure chamber is provided with a plug 59, the purpose of which is to permit the bleeding of air out of the system when initially charging the pressure chamber with fuel, for it is desirable that this chamber be filled to a point near its top and that the space above the surface of the liquid be a vapor space rather than an air space.

In Figure 5 of the drawing I have shown a modified form of float valve mechanism wherein the valve opens in the direction of the flow of liquid from the pump into the pressure chamber. Here the valve seat 13 is below the passage 10 and the valve 14 seats upwardly against said seat 13. With this type of arrangement, it is of course desirable to pack the valve stem so that fuel from the pump will not bypass the valve in entering the pressure chamber by passing through the clearance space between the valve stem and its guide. Consequently the valve stem in the structure of this figure has its upper portion 15a of the non-circular curvilinear cross section shown in Fig. 3, while substantially the lower half 15b of the valve stem is made circular, so as to satisfactorily operate through a packing 60. To preclude trapping of liquid above the packing and below the valve stem guide, which trapping would tend to render the operations of the float valve sluggish, the fitting is drilled as indicated at 61 to provide one or more holes which will eliminate such trapping of liquid in this space. The structure of Figure 5 is otherwise as shown in Figure 1 of the drawing. In practice the pressure controller 21 may be regulated so as to allow the pump delivery pressure to be varied at will.

The foregoing detailed description sets forth

the invention in its preferred practical form, but the invention is to be understood as fully commensurate with the appended claims.

Having thus fully described the invention, what I claim as new and desire to secure by Letters Patent is:

1. The method of operating an internal combustion engine having a cylinder with a piston therein which comprises: introducing fuel under pressure into a pressure chamber, heating the fuel in said chamber to a temperature higher than its boiling point at atmospheric pressure to place it under corresponding elevated vapor pressure, while the fuel remains in liquid condition, introducing air into the engine cylinder, separately feeding fuel from the pressure chamber to the cylinder, while the fuel remains at a temperature above its boiling point and under the said elevated vapor pressure with the fuel in liquid condition, relieving the pressure on such liquid fuel upon its entry into the cylinder whereby it enters the cylinder in vaporized, gaseous condition to

5 admix with the air in said cylinder, thereafter compressing the resulting mixture, and thereafter firing the same, and controlling the pressure feed of liquid fuel into the compression chamber by the liquid level of the fuel in said chamber.

2. The method which comprises: introducing liquid fuel under pressure into a pressure chamber, heating the fuel in said chamber to a temperature higher than its boiling point at atmospheric pressure to place it under a corresponding elevated vapor pressure while the fuel remains in highly heated liquid condition, emitting a quantity of such heated liquid fuel from the pressure chamber and relieving the pressure thereon to cause gasification in the presence of sufficient air to form a combustible mixture, thereafter compressing said combustible mixture and thereafter firing the same, and controlling the pressure feed of liquid fuel into the pressure chamber by the liquid level of the fuel in said chamber.
